Application September 9, 1946, Serial No. 695,682
In Germany June 3, 1941

Section 1, Public Law 690, August 8, 1946
Patent expires June 3, 1961

2 Claims. (Cl. 242—153)

1
This invention relates to the preparation of warp and is more particularly concerned with the high speed preparation of warp from crepe threads.

In warping operations it is customary to support a large number of spools of thread on a creel and to draw the thread overhead from these spools to a beam on which the threads are wound in parallel relationship. During the passage of the threads from the spools to the beam, their path of travel and tension is very accurately controlled by the use of brakes, guides, reeds and the like so that the warp produced will be of high quality and so that the creeling speed may be maintained as high as several hundred meters per minute.

Conventional warping arrangements, as described above, are very efficient in most instances but have been found to be highly unsatisfactory in the warping of crepe due to the fact that crepe thread, if taken off a stationary spool in an overhead manner, tends to form loops and wrinkles that cannot be corrected by conventional creeling brakes, and that are often aggravated thereby. In some cases loops and wrinkles are actually formed by the brakes themselves because a twist is pushed up by the brake.

In view of the foregoing it has been customary in the warping of crepe threads to employ rotatably mounted flanged spools for supporting the thread on the creel, the spool being unwound tangentially rather than overhead. This arrangement is satisfactory so far as the elimination of loops and twists is concerned but is very inefficient as to time consumed in effecting the warping operation, the loss of time resulting from the frictional drag of the rotatable spools which requires a low draw-off speed to prevent thread breakage. It has been found that to avoid breakage it is frequently necessary to reduce the draw-off speed to some thirty meters per minute.

It is therefore an object of this invention to provide warping apparatus that is capable of handling crepe threads at very high draw-off speeds while wholly eliminating the formation of the objectionable loops and twists that characterized the previous efforts of the art in this direction.

Another object of this invention is to provide 50 being driven by the moving thread 1. In order

2
a creel brake which may be applied to an ordinary overhead draw-off installation so that said installation may be used for the high speed warping of crepe threads.

5 Other objects and advantages of this invention will be apparent upon consideration of the following detailed description of a preferred embodiment thereof in conjunction with the annexed drawings wherein:

10 Figure 1 is a view in elevation of a creel brake constructed in accordance with the teachings of the present invention; and

15 Figure 2 is a view in elevation of the creel brake of Figure 1 taken from a point of view 90° away from the viewpoint of Figure 1.

Referring now in greater detail to the drawings, the thread 1 issuing overhead from a bobbin, not shown, is first led through an eyelet 2 in a plate 3 which is supported from a standard 20 4. It then passes behind a roller 5 which is mounted for free rotation on a stud 6, through a finger-like thread guide 7, around the roller 5, through the guide 7 again, around the roller 5 again and finally through the guide 7 and 25 through an eyelet 8 mounted on a lever 9 to the warping beam, not shown.

Upon reference to Figure 1 it will be noted that the roller 5 is provided with a base portion 10 and that the end of the lever 9, remote from 30 the eyelet 8 is provided with a bifurcate brake portion 11 which underlies the base portion 10. As long as the thread 1 is continuous and its tension during passage through the eyelet 8 is sufficient to prevent sagging, the portion 11 of 35 the lever 9 will lie parallel to the base 10 of the roller 5 and the latter will turn freely. However, since the lever 9 is supported by the thread 1 in the position shown in Figure 2 it is apparent that upon thread breakage or sagging, the lever 40 will pivot in a clockwise direction, as viewed in Figure 2, about its pivotal mount 12 in the base of the guide 7, the movement between the eyelet 8 and the pivot 12 being greater than the movement between the pivot 12 and the end of the 45 brake portion 11. This pivotal movement causes the portion 11 of the lever 9 to bear against the base 10 of the roller 5 with braking effect.

In normal operation when the lever 9 is in the position shown in Figure 2, the roller 5 rotates, being driven by the moving thread 1. In order

to prevent slippage of the thread on the roller 5 the latter is provided with a surface of rubber or the like.

The finger-like thread guide 7 is provided with a plurality of thread-leading grooves at 12' which extend circumferentially in axially spaced relation to each other. These grooves are open for most of their length but are closed at a small common arcuate zone by a bridge 13 which defines with the lands on the guide a plurality of small eyelets 14. Upon reference to Figure 1 it will be seen that the thread passes through one of these eyelets each time it passes around the guide, the thread assuming a generally helical path in its passage around the roller 5 and the guide 7. The guide 7 and the stud 6 are supported from the standard 4 which is suitably attached by means not shown to the creel frame.

The plate 3 in addition to the eyelet 2 is also provided with an eyelet 2'. This is done so that the device of the present invention may be used with either S-twist or Z-twist threads, the eyelets 2 and 2' lying on opposite sides of the roller 5, as can be seen upon reference to Figure 2.

In operation the thread 1 is led overhead from a package or the like suitably supported on the creel frame through one or the other of the eyelets 2 or 2', depending upon whether the thread is of the S- or Z-twist type. The thread is then led in a general helical path one or more times around the assembly comprised of the roller 5 and the thread guide 7, a different one of the grooves 12' and eyelets 14 being used for each turn of the thread. It will be understood that the direction of rotation of the roller 3 will vary depending upon which of the eyelets 2 and 2' is used. The number of times that the thread is passed around the roller 5 and the thread guide 7 varies somewhat depending upon the nature of the thread, it being understood that enough turns around the roller and thread guide assembly will be taken to prevent slippage. The roller and thread guide serve to prevent formation of loops and wrinkles in the creeling of crepe. The brake which acts on the roller 5 serves to stop the roller when the thread breaks or when sufficient slack occurs to cause the lever 9 to move to a brake applying position, it being understood that the roller 5 is normally driven by engagement with the thread.

It is to be understood that while the foregoing description is directed to be a single embodiment of this invention, modifications are possible within the scope of the invention as defined by the appended claims.

What is claimed is:

1. An assembly for use in preventing tangling during the overhead unwinding of crepe thread

comprising a vertically mounted sub-assembly including a roller mounted for rotation about a vertical axis and adapted to be driven by frictional contact with the moving thread and a thread guide in substantially parallel spaced relation to the axis of said roller, said guide having a plurality of axially spaced grooves and eyelets therein, means constituting a part of the assembly defining a pair of eyelets in the thread path

5 leading to said sub-assembly, one of said eyelets lying on one side of said roller and the other eyelet lying on the other side of said roller, and means also constituting a part of the assembly defining an eyelet in the thread path leading from 10 said sub-assembly whereby, depending upon the direction of twist of the thread, it may be led first through one or the other of the eyelets in the thread path leading to the sub-assembly, then in a generally helical path one or more times 15 about the roller and through the eyelets of the guide, and finally through the eyelet in the thread path leading from the sub-assembly.

2. A creeling brake for use in preventing tangling in the overhead unwinding of crepe thread 20 comprising a vertically mounted assembly including a roller mounted for rotation about a vertical axis and adapted to be driven by frictional contact with the thread and a guide adjacent said roller, said guide defining a plurality of spaced eyelets, means defining an eyelet in the thread path to said assembly, and a lever pivoted in the base of said thread guide, one end of said lever constituting a brake portion adapted to bear against the underside of said roller to retard rotation 25 thereof, and the other end of said lever having an eyelet therein, said lever being movable from a normal position in which the eyelet end is down and the brake portion is in braking position to a raised position in which the eyelet end is up and the brake portion is in roller releasing position, the eyelet end of said lever being supported in raised position by the thread leading 30 from said assembly, rupture or slack in the thread causing said lever to fall to normal position.
